UNITED STATES PATENT OFFICE

MAXIMILIAN MATHIAS, OF BERLIN, GERMANY, ASSIGNOR TO SIEMENS & HALSKE AKTIENGESELLSCHAFT, OF WERNERWERK, SIEMENSSTADT, NEAR BERLIN, GERMANY

CLASS SIGNALING FOR TELEPHONE SYSTEMS

Application filed December 3, 1928, Serial No. 223,323, and in Germany December 29, 1927.

The invention relates to telephone systems having different classes of stations, which differ from one another for example in the traffic, to which they are entitled, or in the 5 manner, in which their calls are set up.

Now the object of the invention is to notify the operator the class to which a calling station belongs, this being achieved by providing a calling subscriber's station and the 10 operator with a device for each, the co-operation of the two devices notifying to the operator the class to which the calling station belongs.

The arrangement is of particular advantage when the operator's position at the 15 exchange is notified by an audible signal, because the clearness of the conversation is not reduced by the functioning of the devices used for notifying.

Examples of the invention are shown in the Figs. 1 to 4. The rectangles enclosing the windings of various relays shown on the drawing indicate that these relays are made slow to release by placing a copper slug on 25 the heel end of the core, or in some other known manner. The invention is not necessarily limited to these examples. The invention will be further described with reference to these figures.

Figs. 1 and 2 of the drawing, when Fig. 2 is placed to the right of Fig. 1, show by means of the usual schematic diagram the preferred embodiment of the invention. The apparatus shown to the left of the vertical broken line in Fig. 2 is at the coin box station, while that shown to the right of this vertical line is the apparatus in the exchange. Fig. 2 discloses the apparatus at the operator's position.

Fig. 3 shows a modification of the invention in which the oscillator at the operator's position is associated with the service trunks extending to this position.

Fig. 4 shows still another modification in which the oscillator associated with the calling station is provided in the exchange and is connected to the outgoing trunks from the line finders, such as AS1.

The circuits shown in the Figs. 1 and 2 will be described first of all.

Assuming the subscriber N at a coin box instrument wishes to set up a connection over an exchange position, then upon the removal of his receiver his preselector VW is started up over earth, winding of relay R, 55 contact 2t, microphone, repeater Ue1, impulse contact J, switch hook HU, contact 1t, resistance Wi, battery, earth; and the switch hunts for an idle group selector. After the preselector's nonnumerical selection, the relay T is operated over: earth, battery, winding of the relay T, wiper c of the preselector VW, contact 5m, resistance Wi, earth, (parallel thereto overwinding I of relay C, contact 6k, earth). At the contacts 3t and 4t it 60 switches through the junction line to the group selector GW, so that the relays A and B are operated in addition to the relay C. The relay V1 is operated over contact 9c (earth, battery, contact 9c, winding II of relay C, 65 contact 8a, relay V1, earth). The insertion of a coin opens the coin insertion contact MEK, hence the operation of the impulse contact J de-energizes the relay A of the seized group selector at each impulse in known manner. In accordance with the impulses the lifting magnet H is energized over: earth, contacts 12w, 11a, 10v1, lifting magnet H, battery, earth. When the relay 70 V2, which was energized when the short circuit was removed upon the release of the relay A, falls back at the end of the impulse train owing to the short circuit over contact 8a, the group selector hunts owing to the rotary magnet D being energized over: earth, contacts 18k, 17p, 16v2, 15v1, 13d, rotary magnet D, battery, earth. When the group selector has found an idle switchboard position, the relay P is operated over: earth, winding I and II of relay P, contact 20 v1, 75 wiper c1 of the group selector, lead c2, relay A1, battery, earth; by short circuiting its winding II over the contact 19p, relay P marks engaged the junction jack to all further calls. At the switchboard position the calling lamp AL is lighted over: earth, contact 24a1, jack contact k, calling lamp AL, battery, earth. On inserting the 80 answering plug, the calling lamp AL is disconnected at the jack contact K.

At the switchboard position the calling lamp AL is lighted over: earth, contact 24a1, jack contact k, calling lamp AL, battery, earth. On inserting the answering plug, the calling lamp AL is disconnected at the jack contact K. 85

At the switchboard position the calling lamp AL is lighted over: earth, contact 24a1, jack contact k, calling lamp AL, battery, earth. On inserting the answering plug, the calling lamp AL is disconnected at the jack contact K. 90

At the switchboard position the calling lamp AL is lighted over: earth, contact 24a1, jack contact k, calling lamp AL, battery, earth. On inserting the answering plug, the calling lamp AL is disconnected at the jack contact K. 95

At the switchboard position the calling lamp AL is lighted over: earth, contact 24a1, jack contact k, calling lamp AL, battery, earth. On inserting the answering plug, the calling lamp AL is disconnected at the jack contact K. 100

When the operator answers the call, she throws the speaking key in the direction 1 and at the same time presses the key T_a , whereby the heating battery of the cathode 5 of the oscillation generator R_2 is connected up, thus sending an auxiliary oscillation over the repeater U_{e3} to the junction line. This oscillation, which lies outside the range of audibility, in conjunction with the fundamental frequency generated by the oscillating 10 circuit LC at the coin box station and differing slightly from the auxiliary oscillation (for example 5,000 cycles) and also inaudible, gives rise to an interference oscillation, which is audible. This tone notifies the operator at the exchange position that a special station is calling.

By releasing the key T_a , the operator disconnects the auxiliary oscillation. The clearness of speech is not affected, because the oscillation transmitted from the coin box station lies outside the range of audibility. The audible signal therefore depends on two factors, one of which is under the control of the 20 special station and the other being under the control of the exchange operator. No effective signal is given when one of the two factors is suppressed. Hence it is possible to remove the signal, which affects the clearness of 25 speech, without having to use special switching means, which react on the signaling device of the special station.

When the operator sets up over her connecting device a connection, for which a fee 30 has to be paid, she requests the subscriber to insert one or more coins. Thereby different coin contacts (for example MK_1 , MK_2) are operated according to the kind of coin inserted, hence the alteration in frequency at 35 the oscillation generator by means of different signals notifies the operator of the insertion of the coins. The above mentioned connecting device is not completely shown in the Fig. 2 because it does not concern the 40 invention.

At the end of the conversation, the connection is released in known manner.

Fig. 3 shows an arrangement, in which the devices for indicating to the operator the different classes of subscribers' stations are located at the service line.

When the subscriber, by taking down his receiver (Fig. 1), starts up his preselector to hunt as previously described, the preselector 50 is arrested when a free junction line has been found owing to the relay T being energized over the winding of relay C (Fig. 3) and the off normal contact $35k$. Thereupon the contacts of the relay T switch through the subscriber's line to the a and b leads (Fig. 3), thus energizing the windings I and II of relay A over the subscriber's loop. After contact $30a$ has been closed, the relay V is energized over earth, contact $30a$, relay V , battery, earth. Hence the rotary magnet D_1 of

the service switch DW is energized by impulses due to the self interrupter contact $34d1$ in the circuit: earth, contacts $31t2$, $32v$, $33p1$, $34d1$, rotary magnet D_1 battery, earth; and is thus energized until the service switch over its wiper $c2$ finds a potential, which was applied to the test lead over contact $46e$ when relay C was energized. Relay V_1 is energized in the following circuit: earth, contact $36a$, relay V_1 , contact $37a$, battery, earth. For the moment the relay V_2 is still short circuited, but is energized when the contact $37a$ operates during the transmission of the impulse train, and remains attracted during the impulse train, so that it does not fall back until it is short circuited by contact $37a$ at the end of the impulse train. Relays T_1 and P_1 are energized in the following circuit: earth, battery, contact $46e$, relay T_2 , relay T_1 , wiper $c2$ of the service switch DW , windings I and II of relay P_1 , resistance W_1 , earth. Relay T_2 is not operated owing to the high resistance of W_1 . The service switch is arrested when contact $33p1$ opens the circuit for energizing the rotary magnet D_1 . The operator is connected up after the contacts $39t1$, $41t1$ and $44p1$, $45p1$ have been closed. The device for generating oscillations is only indicated diagrammatically in the figure, it can be arranged like the device R_2 in the Fig. 2. As it is connected up over the contacts $42t2$ and $43t2$, in conjunction with the device R_1 at the subscriber's station (Fig. 1) it indicates the subscriber's station. When the operator short circuits the high ohmic resistance W_1 by pressing the key T_a , relay T_2 is energized in the previously described test circuit, hence the oscillation generator is disconnected and it does not interfere with the clearness of speech when the operator speaks to the subscriber.

The connection wanted by the subscriber N is then set up by the operator with her number sender or dial. The sender contact $66z$ energizes the relay T_3 over: earth, contact $66z$, wiper $c2$, of the service switch DW , relay T_3 , battery, earth; and over contact $50t3$ the relay A_1 receives impulses for positioning the succeeding switch in known manner. After impulse transmission the relay C falls back owing to the opening of the off normal contact $35k$ when the switch GW is raised and the relay T_3 falls back owing to the opening of the sender contact $66z$ after impulse transmission. The opening of the contacts $46e$ and $47t3$ then release the service switch DW and the junction line is switched through over the contacts $49t3$ and $51t3$.

When the receiver is hung up at the subscriber's station N at the end of the conversation, the connection is released owing to relay A (Fig. 3) falling back, whereupon relay V_1 also falls back and after it has short circuited the winding I of relay P over the contact $55v1$, the release magnet M of the switch GW

is energized over: earth, off normal contact 65_c, contacts 64_p, 63_{v2}, 61_{v1}, magnet M, battery, earth. The opening of contact 67_m also releases the preselector VW.

5 Fig. 4 shows an arrangement wherein the devices for generating oscillations provided for the calling station are located at the connecting route reached over preselecting devices.

10 When the subscriber N (Fig. 4) takes down his receiver, the relay R is energized over: earth, battery, resistance W_i, contact 70_t, subscriber N, contact 71_t, relay R, earth. Thereby the call seeker AS1 is started up, 15 and until it reaches the calling line, its rotary magnet D receives impulses over: earth, contacts 79_r, 96_d, 80_p, rotary magnet D, battery, earth, the contact 96_d being a self interrupter. On reaching the calling line, the relays T and 20 P are energized in the circuit: earth, battery, resistance W_i, contact 72_r, relay T, wiper c₃ of the call seeker AS1, windings I and II of relay P, contact 77_r, earth. By opening the contacts 70_t and 71_t the relay R is deenergized and the junction line is switched through 25 over the contacts 74_p and 75_p. Thereupon the relay A is energized over: earth, battery, relay A, contact 75_p, wiper b₃ of the call 30 seeker AS1, subscriber N, wiper a₃ of the call seeker AS1, contact 74_p, resistance W_i, earth. Relays T and P are maintained energized in the following circuit: earth, battery, resistance W_i, contact 73_t, relay T, wiper c₃, winding I of relay P, contacts 76_p, 78_a, earth. At 35 the same time as the closing of the contacts 74_p and 75_p switches through the junction line, the oscillation generator is connected up over the points u and v. This oscillation generator corresponds to the arrangement designated by R1 in the Fig. 1.

40 The energizing circuit of the rotary magnet D is opened at contact 80_p. The junction line VL having been taken into use by the subscriber N, the call seeker AS2 is started up to connect up an idle operator, after the relay R1 was energized over: earth, resistance W_i, contact 81_a, junction line VL, contact 98_{t1}, relay R1, battery, earth. Until the seized junction line has been found, the rotary magnet 45 D1 of the call seeker AS2 is energized over: earth, contacts 94_{r1}, 97_{d1}, 95_{p1}, rotary magnet D1, battery, earth. When the junction line VL is found relays T1 and P1 are energized in the following circuit: earth, battery, resistance W_i, contact 85_{r1}, relay T1, wiper c₄ of the call seeker AS2, windings I and II of relay P1, contact 92_{r1}, earth. By 50 opening the contact 98_{t1} relay R1 is deenergized while the junction line is switched through over the contacts 83_{p1}, 84_{p1}. This having been done, the relay A1 is energized over: earth, battery, winding I of relay A1, wiper b₄ of the call seeker AS2, contact 84_{p1}, junction line VL, contact 81_a, resistance W_i, 55 earth. Therefore the relays T1 and P1 are

locked in the circuit: earth, battery, resistance W_i, contact 86_{t1}, relay T1, wiper c₄ of the call seeker AS2, winding I of relay P1, contacts 91_{p1}, 93_{a1}, earth. The energizing circuit of the rotary magnet D1 is opened at 70 contact 95_{p1}. The closing of the contact 87_{a1} lights the lamp L over: earth, contacts 87_{a1}, 89_{t2}, lamp L, battery, earth, thus giving the operator the calling signal. The head set with the device for generating oscillations shown in 75 Fig. 2 is connected to the junction line at the points x and y.

Now follows the usual operation of connecting up the oscillation generator for indicating the calling subscriber's station and the answering of the call by the operator. The latter then sets up the desired connection over the plug and jack, whereupon the relay T2 is energized over: earth, battery, relay T2, plug portion 3, jack bush, earth, while the 80 contact 89_{t2} disconnects the lamp L.

85 After the receiver has been hung up at the subscriber's station N, at the end of the conversation, the connection is released owing to the relay A falling back and at contact 78_a 90 opening the locking circuit of the relays P and T. Also the relay A1 is deenergized by the opening of the contacts 81_a and 82_a. Thereby the locking circuit of the relays P1 and T1 is also opened, so that the junction line becomes free for other calls after the operator receives the clearing signal by the lighting of the lamp L over: earth, contacts 88_{a1}, 90_{t2}, lamp L, battery, earth; and she has withdrawn the plug from the jack. 95 Thereupon the relay T2 falls back and the lamp is extinguished by the opening of the contact 90_{t2}. The connection has now been completely released.

100 What is claimed is:

1. In a telephone system, a calling line, an oscillator associated with said line and arranged to superimpose an alternating current of inaudible frequency thereon, a second oscillator capable of superimposing an alternating current of a different inaudible frequency on said line, and means for connecting said second oscillator to said line to produce an audible beat note indicative of the class of the calling line.

105 2. In a telephone system, a calling line extending to an operator's position, an oscillator associated with said line for superimposing an alternating current of inaudible frequency thereon, a second oscillator associated with said operator's position and arranged to transmit an alternating current of a different inaudible frequency, and means controlled by the operator for temporarily connecting said second oscillator to said line 110 to produce an audible beat note indicative of the class of the calling line.

115 3. In a telephone system, a calling line, means for transmitting an alternating current of inaudible frequency over said line, 120

an operator's position, and means at said operator's position for superimposing an alternating current of different inaudible frequency on said line to cooperate with said first alternating current in producing an audible signal to inform the operator of the class of the calling line.

4. In a telephone system, subscribers' lines divided into different classes, an operator's position, oscillators associated with said lines, another oscillator associated with said operator's position, means for connecting a calling one of said lines with said position, and means for temporarily interconnecting the oscillator associated with the calling line with said operator's oscillator to produce an audible beat note indicative of the class of the calling line.

5. In a telephone system, subscribers' lines divided into different classes, an operator's position, oscillators associated with said lines, another oscillator associated with said operator's position, means for connecting a calling one of said lines with said position, means for temporarily interconnecting the oscillator associated with the calling line with said operator's oscillator to produce an audible beat note indicative of the class of the calling line, and subscriber controlled means for varying the pitch of said beat note.

6. In combination, a line, means for transmitting a signaling current of inaudible frequency over said line, a source of current at the receiving end of the line which is also of an inaudible frequency but which differs in frequency from the signaling current being received, means for connecting said source with the line to produce a heterodyne signal which is audible, and means at the transmitting end of said line for varying the pitch of said signal.

In witness whereof, I hereunto subscribe my name this 5th day of November, A. D. 1928.
